J. Reaney, Kelly & Co., Attorney

UNITED STATES PATENT OFFICE.

WILLIAM S. MONTGOMERY, OF DETROIT, MICHIGAN.

KEYHOLE GUARD AND LOCK.

1,359,190.

Specification of Letters Patent. Patented Nov. 16, 1920.

Application filed April 19, 1920. Serial No. 375,003.

To all whom it may concern:

Be it known that I, WILLIAM S. MONTGOMERY, citizen of the United States, residing at Detroit, in the county of Wayne 5 and State of Michigan, have invented certain new and useful Improvements in Key-hole Guards and Locks, of which the following is a specification.

The present invention relates to improvements in key-hole guards and locks and as 10 its main object, a combined key-hole and lock that may be positioned in the key-hole without removing the key from the lock and which, when in position will prevent the key from being dislodged from the outside, or if there is no key in the lock, prevent 15 the insertion of a key from either the inside or the outside of the lock.

A further object of the invention is to 20 provide a device of the above character which is simple in construction, cheap to manufacture and which may be quickly attached or detached to or from the lock in connection with which it is used.

Various other objects and advantages of 25 my invention will become apparent during the continuance of the following description.

In the drawings:

Figure 1 is a view in cross section of a 30 conventional door and lock showing my invention in place in connection therewith.

Fig. 2 is a view in perspective of the locking tongue of the device which is inserted 35 in the hole.

Fig. 3 is a view in detail of the securing hasp.

In the drawings, I have shown for the 40 purpose of illustration, a door 10 equipped with a conventional lock 11 which has the ordinary key-hole 12. A key 13 is also shown in the lock and the head thereof is slightly out of alinement with the key-hole, the key having been given a partial turn 45 after being inserted in the lock.

My invention, more properly consists of 50 a locking tongue 14 being slightly bent intermediate its ends as at 15 and having its bent end tapered to a point as shown at 16. At its other end the tongue is bent to form 55 a head 17 which lies at right angles to the body of the tongue as clearly shown in Fig. 2. The upper edge of the body of the tongue is cut away to provide a recess 18. Likewise the lower edge of the body of the tongue is cut away as at 19 to form a shoul-

der 20. When the body of the tongue is in place in the key-hole the bent end 16 terminates slightly to one side of the key-hole so that an instrument inserted in the key-hole 60 from the outside cannot be manipulated to dislodge the same and the shoulder 20 abuts the rear wall of the lock as clearly shown in Fig. 1 so as to prevent the withdrawal of the tongue without first raising the same 65 slightly.

I also provide a securing hasp 21. The hasp is provided with a longitudinal slot or channel 22 which receives the body of the tongue as shown in Fig. 1 and is provided 70 with a lug 23 which lies in the cut-out 18 of the body of the tongue also shown in Fig. 1.

From the above it will be observed that when the parts are in the position shown in Fig. 1 and the lower end of the hasp 21 is 75 locked in position it will be impossible to remove the body of the tongue 14 from the key-hole without first releasing the hasp 21. In order to firmly secure the hasp in position and thereby indirectly hold the tongue 80 14 in place, I equip the door 10 with a fastening member 23. The fastening member is provided with a head 24 so that when the head 24 is in an upright position the hasp can be readily slipped thereover, the shank 85 of the fastening member extending through the opening 22. The head of the fastening member is then turned downwardly as shown in Fig. 1 and thereby locking the hasp in place.

The tongue 14 as well as the hasp 21 may be made any suitable size so that it can be used in connection with different sized locks and may be made of different kinds of material, as is satisfactory.

From the foregoing it is believed that the 95 advantages and novel features of my invention can be readily understood and therefore further detailed description is deemed unnecessary.

What is claimed is:

1. In a key hole guard and lock, a locking tongue having one end offset with respect to the body thereof and adapted to be inserted in the key hole of the lock the offset 105 end thereof being out of alinement with the key hole, a head formed at the other end of said tongue, a hasp having a slot receiving the body of said tongue, and means to lock said hasp in position.

2. In a key-hole guard and lock, the combination with a door and lock, of a locking

- tongue comprising a body portion positioned in the key-hole of said lock, said body portion being bent intermediate its ends, the inner end thereof being out of alinement with said key-hole, a head on said tongue exterior to said lock, said tongue being cut away along its lower edge to provide a shoulder, said shoulder projecting below the key-hole opening of said lock to prevent withdrawal of said tongue, a hasp having a longitudinal slot receiving said tongue, and a fastening member on said door securing said hasp against upward movement substantially as described.
- 15 3. In a key hole guard and lock, a locking

tongue adapted to be inserted in the key hole of the lock, one end of said tongue being offset to lie out of alinement with the key hole, a head formed at the other end of said lock, said tongue being cut away along 20 its lower edge to form a shoulder, said shoulder projecting below the key hole opening of the lock, said tongue being also cut away along its upper edge, a hasp having a longitudinal slot receiving the body of 25 said tongue, a lug on said hasp fitting said last named cut away portion, and means to secure said hasp in place.

In testimony whereof I affix my signature
WILLIAM S. MONTGOMERY.
